UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

DRAWER-LOCK FOR TRUNKS.

1,264,321.

Specification of Letters Patent. Patented Apr. 30, 1918.

Application filed March 10, 1915. Serial No. 13,490.

To all whom it may concern:

Be it known that I, FRANK W. MEYER, a citizen of the United States, and resident of Oshkosh, in the county of Winnebago and 5 State of Wisconsin, have invented new and useful Improvements in Drawer-Locks for Trunks, of which the following is a description, reference being had to the accompanying drawings, which are a part of this specification.

10 This invention has for its object to provide a locking means for simultaneously locking all of the drawers in a wardrobe or bureau trunk, which locking means will be 15 simple and inexpensive, and will not mar the ornamental appearance of the trunk, or occupy valuable space therein.

With the above and other objects in view 20 the invention consists in the drawer lock for trunks as herein claimed, and all equivalents.

25 Referring to the accompanying drawings, in which like characters of reference indicate the same parts in the different views,

20 Figure 1 is a rear elevation of the drawer section of a wardrobe or bureau trunk provided with the locking means of this invention, the trunk walls being sectioned to show the drawers and locking means;

30 Fig. 2 is a vertical sectional view thereof;

Fig. 3 is an enlarged detail view of the upper portion of the locking device showing the key controlled operating shaft;

Fig. 4 is a similar view of the lower portion 35 of the locking means showing the offset portion of the locking rod with its hook for engaging the loop on the rear of the invertible drawer;

Fig. 5 is a detail view of the crank arm 40 for moving the locking rod;

Fig. 6 is a front view of the key engaging end of the operating shaft;

Fig. 7 is a detail plan view of the locking hook on the rear of the drawers;

45 Fig. 8 is a similar view of one of the slotted guide plates for the locking rod;

Fig. 9 is a similar view of the locking loop of the invertible drawer; and,

Fig. 10 is an end view of the key.

50 In these drawings 10 indicates the drawer section of a wardrobe or bureau trunk which is preferably provided with horizontal partitions 11 and 12, and has a series of drawers 13 slidably mounted therein in any usual manner, except that the second drawer from

the bottom is designed to be inverted, and its bottom is hinged to permit it to form a hat box with the lowermost drawer.

At the upper end of the trunk section, above the front of the drawers, is a fixed 60 front plate 14 containing a tubular sleeve 15 which is slightly flaring at its outer end to facilitate the entrance of a key 16. A shaft 17 has its flanged end fitting in the end of the sleeve 15 and adapted to be engaged by 65 the slotted end of the key so as to be turned thereby, the other end of the shaft being journaled in a bearing cleat 18 secured to the back of the trunk section, and a squared shouldered portion of the shaft 17, directly 70 in front of the bearing cleat 18, fits within a square opening in the end of a crank arm 19, the other end of which is pivotally connected to the upper end of a vertical locking rod 20. At the lower end of the locking rod 75 20 is pivoted a link 21 approximately parallel with the crank arm 19 and pivotally connected on a stud 22 in the back of the trunk section. The length of the link 21 being approximately the same as that of the 80 crank arm 19 the turning of the operating shaft 17 by means of the key 16 serves to lift the locking rod 20 and at the same time move it laterally to the vertical position shown in dotted lines in Fig. 1. Each 85 drawer 13, except the invertible drawer, is provided at its rear end with a hook 23 so positioned that the locking rod 20 in its raised position is out of the line of travel of the hook in the sliding movements of the 90 drawer, but when the drawer is closed and the locking rod is moved to its lower position it enters in front of the free end of the hook so as to prevent the sliding movements of the drawer. With the invertible drawer, 95 however, such a hook member correctly positioned for engagement with the locking rod in the upright position of the drawer would be in the wrong position for such engagement in the inverted position of the 100 drawer, and consequently this drawer instead of having a hook on its rear end is provided with a loop 24, and the locking rod 20 is bent to give it an offset portion back of this drawer, and in the offset portion is 105 secured a downwardly extending hook 25 adapted to enter the loop 24 in the downward movement of the locking rod 20, and thus securely lock this drawer at the same time the other drawers are locked. This 110

manner of engaging the invertible drawer by the locking rod is effective in either the upright position of the drawer or the inverted position thereof. In order that the locking rod may be guided in its movements slotted guide plates 26 may be secured to the rear edges of the partitions 11 and 12, and the locking rod passes through the slots thereof.

- 10 By means of this invention the drawers of the trunk may be quickly locked by the turning of the key 16, so that the contents thereof are protected without the necessity for closing and locking the trunk. The 15 turning of the key serves to turn the shaft 17 and thereby swing the crank arm 19 and also the locking rod 20, while at the same time moving it laterally into engagement with all of the hooks 23, the hook 25 entering 20 the loop 24 at the same time because of the lowering movement of the locking rod. When the key is turned in the other direction the locking rod is lifted and swung laterally so as to release the hooks 23 and the 25 loop 24, so that the drawers are again available, and this operation is the same in either position of the invertible drawer.

What I claim as new and desire to secure by Letters Patent is:

- 30 1. In a trunk having a section containing sliding drawers positioned one above another, swinging arms on the back of the trunk section, a vertical locking rod carried by the swinging arms and adapted to be lifted and moved laterally thereby, hooks on the rear ends of the drawers engaged by the edge of the locking rod, one of the drawers having a loop on its end instead of a hook and being adapted to be inverted to 35 form a hat box with the drawer beneath, and a hook on the vertical rod to engage said loop in either position of said drawer.

2. In a trunk having a section containing sliding drawers one above another, swinging 40 arms on the back of the trunk section, a vertical locking rod carried by the swinging arms and adapted to be lifted and moved laterally thereby, a vertically extending 45

hook on the locking rod, a loop on the end of one drawer adapted to be engaged by 50 said hook whether the drawer is upright or inverted and hooks on the ends of the other drawers engaged by the edge of the locking rod when the latter is in its locking position and adapted to be disengaged by the 55 lateral movement of the locking rod as it is moved to disengage the loop.

3. In a trunk having a section containing sliding drawers one above another, a key controlled rod mounted in said trunk section, approximately parallel swinging arms on the back of the trunk section one of which is connected to the said rod, a vertical locking rod carried by the swinging arms and adapted to be lifted and moved laterally thereby, a longitudinally extending hook on the locking rod, a loop on the back of one of the drawers adapted to be engaged by said hook whether the drawer is upright or inverted, projecting hooks on the backs of other drawers to be engaged by the edge of the locking rod incident to the lateral movement thereof.

4. A trunk having parallel partitions dividing it into drawer spaces, a drawer slidably fitting in each drawer space, metal plates secured to the rear edges of the partitions and overhanging such rear edges with elongated slots in their overhanging portions, a pair of links pivotally mounted at the back of the trunk, a locking rod carried by the pair of links and adapted to have longitudinal as well as lateral movement, said locking rod passing through the slots of the guide plates and extending 85 across the rear ends of the drawers, and locking members on the rear ends of the drawers engaged and disengaged by the locking rod as the result of such movements.

In testimony whereof I affix my signature 90 in presence of two witnesses.

FRANK W. MEYER.
